SCRAPER

Abraham Abrahamsen, Queens Village, N. Y.

Application June 16, 1950, Serial No. 168,612

3 Claims. (Cl. 30—171)

1

This invention relates to a scraper for smoothing and finishing wood surfaces and the like and in particular a scraping tool to which pressure is applied directly over the blade.

In the present invention, I construct a sturdy scraper of light materials with blade, head and handle assembled to reinforce each other so as to form a rigid structure.

In carrying out my invention I provide a head made of a pair of clamping plates which form reverse angles with a connecting shank so that a removable blade can be held in place. This blade, in the shape of an elongated Z, has one flange securely mounted behind the shank of the head while the second flange is in scraping position. In use, I find that to make the scraper an efficient smoothing tool it should not be resilient to uneven surfaces. I solve this difficulty by making my handle U-shaped with the upper bar elongated to clamp directly to the blade and head, forward of the shank. When this is done the upper bar to which pressure is applied conveys this pressure forward of the shank so as to make my structure rigid and obviate bending of the head. The lower bar of the handle is also clamped to the head but rearward of the shank. This makes an open loop which protects the knuckles against banging on the work.

By thus locating the handle where it will give the necessary reinforcement to the head, I make my structure so strong and rigid that I may use light materials to construct an inexpensive scraper which has been shown in operation to be sturdy and efficient. This construction also enables me to use a very thin Z-shaped blade easily removed and reversed which I strengthen by bowing the two flanges to form shallow cylindrical segments.

This invention can readily be understood by reference to the accompanying drawing in which Fig. 1 is a top view of the scraper; Fig. 2 is a side elevation view; Fig. 3 is a perspective view of the blade; Fig. 4 is a perspective view of the head and Fig. 5 illustrates this invention in a modified form.

Scraper 10 as illustrated in the drawing has a removable blade 12 with a pair of reversible cutting edges 14 on flanges 16. These flanges form reverse obtuse angles 18 with the body of the blade. In the preferred form of my invention shown, I strengthen flanges 16 by curving or bowing them to form shallow cylindrical segments. With these cylindrical segments I may automatically vary the depth of cut. For instance, by rotating the scraper in a counter-

2

clockwise direction, cutting edge contact with the work is decreased. This increases the pressure on the center portion of the blade so that it penetrates the work to give a deeper cut.

Head 20 adapted to carry blade 12 has two clamping plates 22 and 24 and a connecting shank 26. Clamping plate 22 and shank 26 form an obtuse angle 28 similar to obtuse angle 18 so that one flange of the blade fits snugly against the shank and the second flange is held approximately perpendicular to the working surface (see Fig. 2). In scraping, I slide cutting edge 14 across the work only in the direction of the handle and prevent twisting of the blade by fitting one flange against shank 26. This also distributes the force required to slide the scraper over rough surfaces to substantially the entire flanged area held behind shank 26. Otherwise this force is transmitted solely by a clamping bolt which might have a tendency to distort the blade. Thus, I may use a very thin blade easily sharpened by a burnisher reducing the necessity for frequent grinding. It is to be noted that the idle blade cannot be damaged in its protected position behind the shank.

Clamping plate 24 extends at an approximate right angle from shank 26 and mounts a U-shaped handle 30 by lower bar 32. Upper bar 34 is elongated and curved over shank 26 to form extension 36. I find that by clamping extension 36 forward of the shank, the bearing pressure of scraping is applied directly over the blade to obviate bending of the head, and the scraper is materially strengthened.

The blade and handle may be clamped to head 20 by any desired means but the important thing is that the blade may be easily replaced. For this purpose, I show in Fig. 2 a screw and wing nut indicated at 38 for holding upper bar 34 of the handle and blade 12 to clamping plate 22 by means of corresponding holes 40 and lower bar 30 is mounted on clamping plate 24 by rivets 42 and corresponding holes 44. Any suitable material may be used to form my scraper but I prefer to make the blade out of carbon steel approximately 25-30 thousandths of an inch thick and to construct the head and handle of aluminum.

A modified form of this invention is shown in Fig. 5 with the blade detached and shown immediately below the head. In this modification the angles of the blade and head members are identical with the primary form of my invention. Scraper 46 has a removable blade 48 with a pair of reversible cutting edges 50 on flanges

52. On either side of the central portion of the blade are notches 54. Head 56 has two clamping plates 58 and 60 with connecting shank 62. Tabs 64 located on either side of clamping plate 58 are adapted to fit tightly into notches 54 when a blade flange 52 is in position against shank 62. Normally flange 52 prevents twisting of the blade but when worn off by repeated sharpening it tends to become less effective and in such case tabs 64 and notches 54 cooperate to prevent blade twisting. Handle 66, in the general form of a U, has a lower bar 68 and an upper bar 70 elongated and curved over shank 62 to form extension 72. The opposite closed end of the handle is also curved and extended to form guard 74 for knuckle protection. So formed this modified scraper may be assembled by the same means shown in Fig. 2 and described above.

It will be understood that it is intended to cover all changes and modifications of the preferred embodiment of this invention herein chosen for the purpose of illustration which do not constitute departures from the spirit and scope of the invention.

What I claim is:

1. In a device of the type described, a two-edged removable blade in the general form of an elongated Z, comprising a central portion and two flanges, said flanges having cutting edges, each flange forming an obtuse angle with the central portion and each of said edge portions being bowed to form a shallow cylindrical segment, a head comprising a body portion, a clamping plate adapted to receive the central portion of said blade and a connecting shank which holds the blade clamping plate at an obtuse angle with said body portion, a looped handle in the general form of a U having a long and short arm, said short arm being connected with the body portion of said head and said long arm being connected with said blade clamping plate of the head to apply bearing pressure over the entire central portion of the blade when scraping, readily detachable means for clamping the blade to said blade clamping plate of the head, one flange of said blade being covered by the head and said obtuse angles of the head and blade cooperating to hold the second edge

perpendicular with the work when the handle is held parallel with said work.

2. A structure as specified in claim 1 in which the closed end of the U-shaped handle is curved and extended below the horizontal plane of the lower arm to form a guard to protect the knuckles against banging on the work.

3. In a device of the type described a two-edged removable blade in the general form of an elongated Z comprising a central portion and two flanges, said flanges having cutting edges, each flange forming an obtuse angle with the central portion and each of said flanges being bowed to form a shallow cylindrical segment, the blade having a notch centrally located on either side of its central portion, a head comprising a body portion, a clamping plate adapted to receive the central portion of said blade and a connecting shank which holds the blade clamping plate at an obtuse angle with said body portion, said head having a pair of tabs, each tab being centrally located on either side of said blade clamping plate of the head and adapted to fit said blade notches, a looped handle having a long and short arm, said short arm being connected with the body portion of said head and said long arm being connected with said blade clamping plate of the head to apply bearing pressure over the entire central portion of the blade when scraping, readily detachable means for clamping the blade to said blade clamping plate of the head, one flange of said blade being covered by the head and said obtuse angles of the head and blade cooperating to hold the second flange perpendicular with the work when the handle is held parallel with said work.

ABRAHAM ABRAHAMSEN.
